PICTURE FRAME OR SIMILAR ARTICLE

Jonathan Turner, Chicago, Ill., assignor to Turner Manufacturing Company, Chicago, Ill., a corporation of Illinois

Application August 3, 1955, Serial No. 37,298

Term of patent 14 years

(Cl. D29—20)

FIG. 1.

FIG. 2.

FIG. 3.

Fig. 1 is a front elevational view of a picture frame or similar article showing my new design;

Fig. 2 is a side view thereof; and

Fig. 3 is a section on the line 3—3 of Fig. 1.

I claim:

The ornamental design for a picture frame or similar article, substantially as shown.
